(57) **CLAIM**

The ornamental design for an assembly wash station, as shown and described.

DESCRIPTION

FIG. 1 is a perspective view of an assembly wash station showing a new design;

FIG. 2 is a front view of the station of FIG. 1;

FIG. 3 is a rear view of the station of FIG. 1;

FIG. 4 is a left side view of the station of FIG. 1;

FIG. 5 is a right side view of the station of FIG. 1;

FIG. 6 is a top view of the station of FIG. 1;

FIG. 7 is a bottom view of the station of FIG. 1;

FIG. 8 is a perspective view of the station of FIG. 1;

FIG. 9 is a perspective view of an assembly wash station showing a new design;

FIG. 10 is a front view of the station of FIG. 9;

FIG. 11 is a rear view of the station of FIG. 9;

FIG. 12 is a left side view of the station of FIG. 9;

FIG. 13 is a right side view of the station of FIG. 9;

FIG. 14 is a top view of the station of FIG. 9;

FIG. 15 is a bottom view of the station of FIG. 9; and,

FIG. 16 is a perspective view of the station of FIG. 9.

The broken lines shown in FIGS. 1-16 are for the purpose of illustrating environmental structure and form no part of the claimed design.
